UNITED STATES PATENT OFFICE.

JOSEPH SACHS, OF HARTFORD, CONNECTICUT.

ELECTRIC SWITCH.

1,257,533.

Specification of Letters Patent. Patented Feb. 26, 1918.

Application filed February 18, 1915. Serial No. 9,059.

To all whom it may concern:

Be it known that I, JOSEPH SACHS, a citizen of the United States, residing at Hartford, in the county of Hartford and State 5 of Connecticut, have invented certain new and useful Improvements in Electric Switches, of which the following is a specification.

This invention relates to electric switches. 10 An electric switch involving the invention can be used with advantage in many different connections, but it is of particular utility when used in conjunction with electromagnetic actuating mechanism, and when so combined it functions as a remote control switch. 15 Among the principal objects of the invention are the provision of an article of the character set forth which is simple in construction and positive and certain in action. 20 In the drawings accompanying and forming part of the present specification I have shown several of the many forms of embodiment of the invention which will be set forth in detail in the following description. 25 I do not restrict myself to this disclosure; I may depart therefrom in radical respects within the scope of the invention defined by the claims following said description.

Referring to said drawings: 30 Figure 1 is a side elevation of one form of electromagnetically actuated remote control switch involving my invention, parts being in section and broken away.

Fig. 2 is an end elevation as seen from the 35 right in Fig. 1.

Fig. 3 is a detail view showing a part of the switch bar actuating mechanism illustrated in Fig. 1 but in a different position.

Fig. 4 is a perspective view of one form 40 of what I term movement controlling contacts.

Fig. 5 is a diagram of circuit connections which may be used in connection with the switch shown in the preceding views. 45 Figs. 6, 7 and 8 are diagrams of other forms, all hereinafter more particularly described.

Like characters refer to like parts throughout the several views.

50 In Figs. 1 to 4 inclusive of the drawings I have shown the electromagnetic actuating device as an electric motor, the two electromagnetic elements thereof being the field magnet and the armature, and said device 55 is adapted to move the switching mechanism into on and off positions in alternation and

preferably also causes the action of the movement controlling contacts. In Figs. 5 to 8 inclusive I have shown diagrams of the main and remote control circuits as well as a remote control circuit opening and closing device or as it may be called main switch controller. In Fig. 5 the electromagnetic actuating element is like that shown more in detail in Figs. 1 to 4 inclusive, while in Figs. 6, 7 and 8 the electromagnetic actuating devices and switching mechanism are of different kinds.

Referring first to Fig. 5 the field magnet winding is denoted by 2, the armature with its commutator being designated by 3 and the armature shaft by 4. The main switch involves a movable member such as the bars or arms 5 and 6 shown in the off or open circuited position but which when in the on or closed position connect the contacts 7 and 8 and 9 and 10 respectively. The supply or feeding wires of the two wire circuit are denoted by 11 and 12, while the wires to the translating device or devices are designated by 13 and 14, the translating device being designated by 15. There are two movable contactors as 16 and 17, the contactor 16 being in constant engagement with and adapted to slide or roll against the stationary contact plate, rod or bar 18, while the contactor 17 bears a similar relation to the bar, rod or plate 19. These movable contactors 16 and 17 as will be understood act as terminals from the armature brushes, the contactor 16 being connected through the bar 18 and suitable conductor to one commutator brush, while the contactor 17 is connected through the part 19 and a suitable conductor to the other commutator brush. 90 The movable contactors 16 and 17 are cooperatively movable with the bars or arms 5 and 6 which latter are mechanically connected to move as a unit and preferably, though not essentially, carrying the two contactors which with the bars 5 and 6 are insulated from each other. In addition to the movable contactors there are preferably stationary contacts such as 20 and 21 and 22 and 23 arranged in coöperating pairs and one movable contactor being coöperative with each pair of stationary contacts, which latter may consist of clips, fingers, plates or something of other suitable nature, the contactor 16 as shown coacting with the contacts 20 and 21 while the contactor 17 co-operates with the contacts 22 and 23. The

switch-control make-and-break device by means of which the operation of a switch is controlled and which may be located at any desired control point may be of any suitable kind, comprising as shown the central pivoted contacting arm 24 and the stationary contacts 25 and 26. The arm 24 is shown provided with operating push buttons of insulating material one at each side 10 of its center of oscillation, so that it may be moved into connection with either the contact 25 as shown or into connection with the contact 26.

It will be noted that the stationary switch 15 movement control contacts 21 and 22 are connected together and that both of these contacts are in turn connected by a suitable conductor with one terminal of the field magnet winding, the other terminal of the 20 latter being connected to one side of the circuit, which in the diagram is the conductor or wire 11. The contacting arm of the switch control make- and break- device is connected to the other side of the circuit, 25 as shown the wire 12. It will be understood that it is not necessary to run a wire from the remote control point back to the main switch, as this connection may be made at any point so long as the arm 24 or its 30 equivalent is connected to the circuit at the opposite side of that to which the field magnet winding is connected. The stationary contact 20 is electrically connected with the stationary contact 26, while the contact 23 35 is electrically connected with the stationary contact 25. For simplicity I have not shown the holding, fastening or attaching means between the armature shaft and the switch bars 5 and 6 and movable contactors 16 and 40 17. In the form of switch shown in Figs. 1 to 4 inclusive the electromagnetic actuating device is adapted to initiate the movements of the switch member made up of these two bars 5 and 6, final movements being 45 completed by spring means tensioned on said initial movements as will herein-after more particularly appear.

In the diagram (Fig. 5) the main switch is shown in the off or open circuited position. To put the switch into this position 50 it was necessary to operate the switch controller at the remote control point and by bringing the arm 24 against the stationary contact 25. In order now to close the main switch it is necessary that the circuit controller arm 24 be moved into engagement with the stationary contact 26. It will be assumed that this has been done in which case current will flow from one side of the 55 main circuit, the wire 12 (as shown) to the arm 24, contact 26, and by the connecting wire to the contact 20, movable contactor 16, bar or rod 18 and from thence through the connecting wire to one of the commutator 60 brushes of the armature 3, through the

winding of said armature to the other commutator brush, through the connecting wire to the bar or rod 19, movable contactor 17, contact 22, by the connecting wire to the field magnet winding 2 and from the field 70 magnet winding to the opposite side of the main circuit which as shown is the wire 11. Consequently the current in the control circuit is passed through the series connected switch operating motor in such manner that 75 the current flows through the armature in a direction to effect the rotation of the armature shaft 4 and through the latter and co-acting means the movement of the main contact bars 5 and 6 into connection with the 80 contacts 7 and 8 and 9 and 10 respectively, the movable contactors 16 and 17 at the same time being moved away from the stationary contacts 20 and 22 respectively and into connection with the contacts 21 and 23 re- 85 spectively. It will now be understood that the movable contactors 16 and 17 are constantly in connection with the commutator brushes, serving in fact as movable contact terminals for said brushes. It will be sup- 90 posed that the main switch is in the on or closed circuit position and that it is desired to open the main circuit. To accomplish this it is necessary to operate the arm or lever 24 to move it in connection with 95 the contact 25. In this case the current from the conductor 12 passes to the arm or lever 24, contact 25, contact 23, movable contactor 17 to the armature 3 from which it passes to the movable contactor 16, contact 21, field magnet winding 2 and to the other side of the circuit. It will be noted 100 that the direction of the current through the armature 3 has been reversed from the direction of the current which existed previously, although the direction of the current through the field winding has remained as before. In view of the automatic operation of the reversing armature connection performed by the movable contactors 16 105 and 17 coöperating with the stationary contacts 20 and 21 and 22 and 23 respectively, the rotative movement of the switch actuating armature is automatically governed or controlled so as to secure in the arrangement shown reversals in rotation of the armature shaft 4. It will also be obvious 110 that after the main switch controller arm 24 has been actuated to engage either the contacts 25 or the contact 26 and necessarily 115 out of contact with the other thereof, the operation and movement of the movable contactors 16 and 17 also automatically breaks the connection of the control or motor circuit, so that the connection at the 120 main switch controller 24 after having been once made need not be broken, because the circuit is automatically broken through the intervention of the movable contactors 16 and 17 into their new position, and when 125 130

the latter is assumed, the electromagnetic actuating device will be conditioned to effect a reverse action of the main switch. That is to say after the switch controller 24 is once actuated to effect either the on or the off movement of the main switch motor, the circuit through this controller and associated devices is automatically opened at the main switch and the armature of the switch actuating motor reversely connected.

The contacts 20 and 22 with which the movable contactors 16 and 17 are respectively coöperative may be said to be the "on movement contacts," because the contactors 16 and 17 must be in connection with these contacts 20 and 22 to produce a proper circuit arrangement for an on movement of the motor when the controller switch arm 24 is actuated and brought into contact with the controller contact 26 which may be called the "controller on contact" and which is connected with the contact 20, and this wire so connecting these contacts 20 and 26 may be called the "controller on wire." Now in contradistinction to the above the contacts 21 and 23 of the switch movement controlling mechanism or contacting arrangement may be called the "off movement contacts," because the contactors 16 and 17 are in connection with these contacts 21 and 23, respectively when the switch motor actuating armature is properly connected to produce the off movement of the motor when the circuit is properly closed through the contact 25 by means of the lever 24, and therefore the contact 25 of the controller may be called the "controller off contact," and the connecting wire between 23 and 25 may be called the "controller off wire."

The main switch bars 5 and 6, and the attached contactors 16 and 17, are preferably snapped into the on or off position by spring energy, the spring means used for this purpose being tensioned by the motor. After the spring has been tensioned the requisite extent, it is released and caused to impart energy to the said bars 5 and 6 and contactors 16 and 17. Consequently there is an interval between the starting of the armature rotation and the actual snapping into on or off position. For that reason it is desirable that the controller used with this form of my remote control switch, be of a type which when pushed into the on or off position remains in that position, so that the control circuit, through its on or off controller wire, remain closed to permit the continued rotation of the motor until its circuit is automatically broken by the movement of the movable contactors 16 and 17. It will, however, be understood that the same purpose would be accomplished if the controller bar 24 instead of remaining in connection with either contacts 25 or 26, after once being pushed into connection with either of these

contacts, be held in connection for a short interval. It will also be obvious that instead of continued contact with either the contacts 25 or 26, a number of successive contacts may be made where the operator finds he has not held the contact bar down long enough; it being understood that after the main switch has once snapped to on or off, further contacting between the bar 24 and either the contacts 25 or 26 will produce no further movement of the motor, because the on or the off controller wire or circuit has then been disconnected or open circuited by its coacting contactor 16 or 17.

Referring now to the structural embodiment illustrated in Figs. 1, 2, 3 and 4; 30 is a base of insulating material, serving to support and hold the electromagnetic actuating mechanism, and the circuit opening and closing parts. The actuating electric motor 31 has the armature 3, with the commutator of which commutator brushes 33 and 34 contact. The field magnet 35 has the single coil winding 2, one terminal wire of which is indicated by 37, and the other terminal wire by 38. 39 and 40 are the terminal wires extending from the commutator brushes 33 and 34 respectively. To support and hold the motor, four posts 41, 42, 43 and 44 may be provided. The lower end of each of these posts is shouldered, and the decreased diameter portion of each post extends through the insulating plate 45, and through apertures in the base 30 into recesses in the lower surface of the base to which the posts and their attached or secured parts, are firmly held by the nuts like 46 secured to the threaded end of each of the posts. The upper end of each of the posts 41, 42, 43 and 44 has an enlarged portion 45. Each of the posts 41 and 42, including the enlarged portion 45 thereof is made of a single piece of metal, but the enlarged portions of the posts 43 and 44 are each made of insulating material. The motor is secured to the top of the four posts, 41, 42, 43 and 44 by screws as 48 passing through the field magnet frame of the motor and into the enlarged upper portion of each of the posts, as indicated in connection with the sectional view of the insulating enlarged portion 47 of the post 44. While the motor is thus securely and firmly held to the base, and while the posts 41 and 42, due to their all metal construction, are conductively connected to the field magnet frame of the motor, it will be noted that the posts 43 and 44 are each insulated from the field magnet frame, and from each other, as well as from the other posts 41 and 42. Extending across from the post 41 to the post 43, and from the post 42 to the post 44, are the stop bars 49 and 50 respectively, made of insulating material. The stop bar 50 is secured to the post 44 by being clamped between the shouldered upper end of the

metallic portion and the insulating enlarged portion 45, while the other end of the stop bar 50 is held against the shoulder of the enlarged portion 45 of the post 42 by pins, screws or other means. The stop bar 49 is secured at one end to the post 43 by being clamped by the shouldered upper end of the metallic portion of this post and the insulating enlarged portion 45, while the other end of the stop bar 49 is secured to the post 41 in a manner similar to that used in connection with the corresponding end of the stop bar 50.

It is intended that the posts 43 and 44 should act as contact slide terminals for the two conductors extending from the commutator brushes of the motor armature, and for that purpose the conductor 40 connects with the post 43 through the medium of the threaded washer 51, and the wire 39 connects with the post 44 through the medium of the threaded washer 52. These washers it will be noted are located between the stop bar 49 and the insulating enlarged portion 45 of the post 43, and the stop bar 50 and the insulating enlarged portion 45 of the post 44.

The driving end of the armature shaft extends for some distance beyond the bearing 53, and is provided with the threaded portion 54, the shaft being, however, unthreaded or plain at opposite sides of said threaded portion respectively. The outer or as shown the lower end of the armature shaft is provided with upper and lower thrust collars, suitably held to the shaft, and coacting with the thrust plate held between the base 30 and the insulating plate 45, all as denoted in a general way by 57.

As the particular switch here illustrated is to serve as a two-pole switch, two main switch arms or contact bars as 5 and 6 are provided, each being provided at their ends with resilient contact fingers as 59. Consequently one of said bars serves to open or close the circuit across a pair of coacting contacts like 60 in one pole of the circuit, while the other bar serves to open and close the connection across another pair of coacting contacts like 60 in the other pole of the circuit, it being understood that these contacts like 60 are suitably held to the base 30, and are provided with means as indicated for connecting to them the circuit wire, one contact of each coacting pair being connected to a feeding wire, while the other contact of each pair is connected to a translating device wire. The two switch arms or bars 5 and 6 are mechanically held together but insulated from each other in some suitable way as by the insulating rods or coupling pieces 59'. The rods 59' are shouldered at each end so that the end portions of decreased diameter may be received in perforations in each end of the switch arms, said rods being held in place by screws

passed thereinto from the outer side of each of the switch bar arms 5 and 6. These rods, however, while thus holding the switch bars or arms together, are permitted to turn in the apertures in which their shouldered ends 70 are received and held.

The nut 61 is threaded to fit the threaded portion 54 of the armature shaft, and is arranged at each end to pivotally receive and hold one end of each of the links 62 and 63; 75 the other end of each of these links being slidably received in an aperture or hole in each of the two insulating switch bar connecting rods 59'. On the links 62 and 63 are the springs 64 and 65; these being placed on 80 each link or toggle rod or bar as 62 and 63, so as to exert their pressure between the nut 61 and the two connected main switch bars or arms 5 and 6, one end of each of the springs pressing against its coacting insulated piece as 59', while the other end of each of the springs presses against a shouldered portion on the nut pivoted end of each of the links, and inasmuch as the other end of each of the links slides freely in its coacting insulating bar connecting rod 59', the springs exert their pressure against the nut and the bars and tend to push the bars to one side or the other of the nut, dependent upon the relative position of the nut to the bars. 85 90 When the nut is in such position in relation to the main switch bars, that the two links 62 and 63 are in axial alinement, then the springs are fully compressed, and their pressure and energy when released by the movement of the nut, either above or below the switch arms or bars, will be exerted against said switch bars or arms, and push them in a direction opposite to that in which the nut has been moved.

Secured to the nut 61, and surrounding the armature shaft extending through and above and below the nut are the springs 66 and 67. These springs act as cushions or buffers for the nut 61, so that when the nut is moved to 100 either end of the threaded portion 54 of the armature shaft, the outer ends of the upper spring 66 and lower spring 67 will strike against the bearing 53 or the thrust device 57 respectively, and thus exert a pressure 105 110 115 against the nut for the purpose hereinafter described.

The two mechanically associated but electrically insulated switch arms 5 and 6 with their associated parts, extend between the 120 rods 41 and 42 and 43 and 44. Said switch arm 5 has mounted in bearings secured to the bar, rollers 68 and 69 of metal and coacting with the rods 43 and 44. The bearings in which the rollers 68 and 69 are 125 mounted and which are secured to the switch arm or bar 5 or that adjacent the rods 43 and 44, are of insulating material, and consequently while the rollers are of conducting material and serve the purpose of acting as 130

moving electrical contacts as well as mechanical positioning devices, they are each insulated from the bar 5 to which they are mechanically fixed. The spindle of the 5 roller 68, as well as that of the roller 69, is of conducting material, and each of these spindles extends at one end beyond the bearing of insulating material in a direction toward the other roller. On the end of the 10 spindle of the roller 68 is a cylindrical contactor portion 70, and on the end of the spindle of the roller 69 is a similar contactor portion 71. The rollers 68 and 69 being in 15 slidable rolling contact with the posts 43 and 44, and being insulated from the switch arm, act also as electrical contacts to connect the movable contactors 70 and 71 with the insulated posts 43 and 44, so that these movable contactors 70 and 71 are in reality the 20 movable terminals of the two armature brushes, moving with the switch bar or arm 5, and being adapted to make connection and contact with certain stationary movement controlling or reversing contacts hereinafter 25 described.

The other switch arm like 6 adjacent to the posts 41 and 42 is also fitted with a pair of rollers like 68 and 69, which, however, 30 coact with and are in rolling engagement with the posts 41 and 42. The bearings, by which these latter rollers are fixed to their respective switch arm 6 are also of insulating material, in order that said switch arm may be insulated from the posts 41 and 42.

35 It will now be seen that the two switch arms 5 and 6 with their associated parts, when each fitted with the rollers like 68 and 69, are held firmly but slidably between the posts 41 and 42, and 43 and 44, so that while 40 the switch arms may be moved back and forth on the posts they are held against rotative movement; that is, the main switch bars or arms are adapted to move toward or from the contacts 60 on the base 30. It will 45 be understood, however, that the movement of the switch arms is limited in the direction toward the motor or away from the contact 60, or what might be called the off position, by the stop bars 49 and 50; while in the 50 opposite direction or in the on position the movement of the switch bars is arrested by the insulating stop pieces 72 which are fixed to the base 30.

Before proceeding further with the 55 description of the other parts of the structure it may be well at this point to discuss in a general way the actuating mechanism which serves to operate the main switch arms 5 and 6. From what has already been stated 60 it will be understood that rotative movement of the motor armature will, due to the engagement of the threaded portion 54 of the armature shaft with the nut 61, cause a movement of the nut longitudinally along 65 said shaft in a direction dependent upon the

direction of rotation of the armature and its shaft; it being understood that the nut is held against rotative movement by its connection to the switch arms through the toggle arms or links 62 and 63. Assuming for 70 instance that the switch arms are against either the upper or the lower stop, let it be assumed that the nut has been moved by the rotating shaft into a position between the two switch arms so that the two links or 75 bars 62 and 63 are axially in alinement. At this point the springs have been compressed to their maximum, and the entire spring actuated toggle is in its central position. A further movement now in either direction 80 toward either of said stops will bring it beyond the center line, so that then the axes of the two toggle bars or links 62 and 63 are out of alinement at which point the force of the springs will be exerted to push 85 the switch bars in a direction opposite to that in which the nut has been moved, and away from the nut as shown in Fig. 3.

Unless the threaded portion of the shaft like 54 were made sufficiently long, the momentum of the motor armature may cause 90 rotative movement even after the switch arms have been snapped and cause the nut to be moved hard up against the bearing 53, or the thrust bearing 57. This binding of 95 the nut against a stop would entail an excessive torque effort on the part of the armature when it was again necessary to operate the switch in the opposite direction, and consequently move the nut away from its tightly 100 bound contact with either of the stops as stated. To prevent this binding of the nut, and also the necessity of making the threaded portion of the armature shaft of greater length, the plain portions of the armature 105 shaft immediately adjacent and at opposite sides of the threaded portion 54 are provided. Rotation of the armature shaft will now cause the nut to be moved along the shaft only so long as the thread of the shaft 110 engages with the thread of the nut, but after the nut has passed entirely beyond the threaded portion at either end of its movement, and is received on either plain portion of said shaft, then no matter whether said 115 shaft continues to rotate or not, the nut will not be moved further. However, it will be necessary to leave the nut so related to the threaded portion that when it is necessary to move the switch in the opposite direction, 120 and consequently again engage the nut with the threaded portion of the shaft to move it reversely along its length, the thread of the nut is brought into ready engagement with either end of the threaded portion 54 of the 125 shaft. For this purpose the springs 66 and 67 are provided. As the nut approaches in its movement either end of the threaded portion 54, the free end of the spring 66, or the spring 67, will be brought up against either 130

the bearing 53 or the thrust plate of the thrust bearing 57. As the nut is moved still further along the shaft, and finally out of threaded engagement with the threaded portion 54, then either the spring 66 or 67 is sufficiently compressed to hold the nut up against the end of the threaded portion 54 of the shaft, so that while continued movement of the shaft in the same direction produces 10 no further motion of the nut along the shaft, yet the nut is in such relationship with the threaded portion 54, so that when the rotative motion of the armature shaft is in the opposite direction, then the pressure of the 15 nut against the threaded portion at either end will cause said nut to come into immediate engagement with the threads of the threaded portion 54, by virtue of which, movement in the reverse direction will at 20 once be imparted to the nut, causing it to move along the shaft to its opposite position and causing the movement of the switch arms 5 and 6 into the opposite position, all as shown in Fig. 3. In this figure, as has 25 already been stated, the toggle link arms 62 and 63 have just been moved out of axial alinement, the springs 64 and 65 being about to impart their energy to the switch arms to move them upwardly and away from the 30 base, or into the off position. In Fig. 1 this off position of the switch arm, nut and connected links is indicated by the dotted lines. At the point above described and indicated in 35 Fig. 3 the nut 61 is still in engagement with one end of the threaded portion 54 of the armature shaft. As shown, the free end of the spring 67 is about to abut against the thrust bearing 57. Continued movement, therefore, of the nut along the shaft in the 40 same direction will further compress the spring, until finally the nut is out of engagement with the threaded portion, at which time it is being pressed up with just enough pressure to produce the desired reengaging 45 relation and also to balance or react against the pressure exerted on the nut by the toggle springs 64 and 65. It will be understood that the action is the same at either end of the movement of the nut, and in Fig. 50 1 the nut is shown positioned on the upper plain portion of the armature shaft and held by the spring 66 against the upper end of the threaded portion 54 and in position to immediately engage with the threaded portion 54 55 when the motor armature is rotated in the proper direction.

In order now that the electromagnetic actuating mechanism such as the motor may function and operate properly, so that its 60 movement will be in the desired direction, and so that the two elements of this single electromagnetic actuating device may automatically be put into proper operative relationship, and automatically connected electrically, to bring about the desired on or off

motion of the parts, it is desirable to provide for the purpose of coacting with the moving armature terminals or movable movement controlling contactors 70 and 71 certain stationary movement controlling 70 contacts, which together with the contactors 70 and 71 may for convenience be called, if desired, a movement controlling or an armature reversing contacting or switching mechanism. In order that these parts may be 75 more fully understood, reference may be had to Fig. 4 which shows these parts, and particularly the stationary contacts in detail. Mounted on the insulating plate 45 is a metallic post 73, provided at its upper end with 80 the resilient contact 74, and at its lower end with the resilient contact 75. Also mounted on the plate 45 are the contacts 76 and 77, each of which is provided with some means, such as for instance the screws shown, for 85 connecting with each of the contacts of 76 and 77 respectively, a switch control circuit wire. The contact 76 may be called an on movement controlling contact, while the contact 77 may be called an off movement 90 controlling contact, and the wire connected to the contact 76 may be called the on controller wire, and the wire connected to the contact 77 may be called the off movement controller wire. The contacts 74 and 75 are 95 on and off movement controlling contacts respectively, but are electrically connected together by the metallic post 73, and connected to this post is one of the terminal wires 38 from the field winding of the 100 motor. The other terminal wire of the field magnet winding is shown connected at 78 to one of the main switch contacts 60, to which one of the main feed or current supply wires is connected. Consequently the field magnet 105 winding 2 is always connected from one wire of the feed or supply side of the switch to the post 73 with its double contacts 74 and 75, so that in one position of the movement controlling contactors 70 and 71, the terminal 110 from the field magnet winding through its contact 74 is on connected, while in the other position when the contactor 70 contacts with the contact 75, it is off connected. Now it will be noted as indicated in 115 Fig. 4 the movement controlling contactors 70 and 71, which act as the terminals of the armature brushes, are in connection with the contacts 75 and 77. Consequently the armature winding is connected across from the 120 contact 75 to the contact 77, and the controlling circuit is extended from one side of the main circuit through the field winding of the motor through the armature windings, to one of the controller wires, and thus to 125 its respective controller contact, and connected and associated parts to the other wire of the main current supplying or feeding side of the main circuit. As shown by full lines of Fig. 4 and also as shown by the 130

parts in full line in Figs. 1 and 2, the movable movement controlling contactors are positioned in contact relation with the off contacts 75 and 77, so that when the remote controller is actuated, and the off wire from the controller to the main switch is connected, the circuit through the motor will be closed to produce a rotation of the armature in a direction to impart such movement to 10 the nut 61 as to cause said nut to be moved toward the switch arms, passing between them, centralizing the toggle links in axial alignment, and then passing beyond the center, causing the toggle springs to act upon 15 the main switch bars 5 and 6 and throw them into the off position. As the main switch bars carry with them the movement controlling contactors 70 and 71, these will be disconnected from the contacts 75 and 77, and 20 thrown into connection with the contacts 74 and 76, placing the armature winding through the medium of its brushes and connected conductors in a reverse connection with relation to the field magnet winding, 25 and therefore when the control circuit is closed through the on controller wire then the switch actuating motor will be operated in the reverse direction, and the main switch mechanism will be moved in the reverse direction 30 to close the main circuit.

The field winding is denoted by 2, the armature by 3 and the main switch bars by 5 and 6 in all of Figs. 1 to 5 inclusive. The contacts 7, 8, 9 and 10, however, of Fig. 5 are denoted by 60 in Figs. 1 to 4 inclusive where they appear, the rods 18 and 19 of Fig. 5 by 43 and 44 respectively in Figs. 1 to 4, the contactors 16 and 17 of Fig. 5 by 70 and 71 respectively of Figs. 1 to 4 and the 40 movement controlling controller connected stationary contacts 20 and 23 of Fig. 5 by 76 and 77 respectively in Figs. 1 to 4 inclusive. I make mention of the foregoing merely to clear up what might be otherwise considered 45 as apparent inconsistencies in the use of reference symbols.

Let it be assumed that the remote control switch like that structurally shown in Figs. 1, 2, 3 and 4 and diagrammatically represented in Fig. 5, is now placed in the main circuit in such location as to make the extension of the main wires to the translating device most economical. The proper controller wires would be extended from the 55 contacts 76 and 77 (20 and 23 in Fig. 5), to the controller, and there connected to their respective on and off contacts of the controller, like those indicated by 26 and 25 of Fig. 5. A wire would also be extended, as 60 has been stated, from the proper side of the main circuit to the controller in addition to the two wires extending from the controller to the magnetically actuated switch. If desired these controller wires may be continued 65 to other controllers placed at other points.

Now it is simply necessary to push or operate the controller mechanism so as to connect either the on or the off controller wire with the wire from the main line, and thus produce the operation of the single electromagnetic mechanism of the main switch to actuate the main switch parts to close or open the main circuit.

Referring now to the diagrammatic arrangement of parts shown in Fig. 6; the 75 electromagnetic actuating mechanism therein represented, includes the stationary bipolar electromagnet having what may be called the field winding 80 mounted and associated with the field magnet frame 81. 80 Arranged to pivotally swing, in coacting polar relationship with the two poles of the stationary field magnet, is the armature 82 with its winding 83 mounted on the shaft, for instance indicated by the dotted lines 84. 85 The armature is the so-called Siemens's shuttle wound type and is adapted to swing or oscillate so that its poles are either in the relative position to the poles of the stationary electromagnet as shown or in the reverse 90 position, this result being brought about by the changing of the direction of the current in its windings; the direction of the current in the stationary field magnet winding remaining fixed. 95

Secured to the armature shaft 84 but insulated therefrom is the main switch bar 85 of the single pole main switch also provided with the stationary contacts 86 to one of which one of the two feeding or current 100 supply wires is connected, and to the other of which one of the two wires to the translating devices is connected. These wires are indicated by 87 and 88 respectively, the other wire or pole of the circuit being indicated 105 by 89.

Also secured to the armature shaft or spindle 84 but insulated therefrom are the two contactors 90 and 91 and the two terminals of the armature coil or winding 83 are 110 each respectively connected to one of these contactors which represent and act as the armature winding terminals, and due to their mechanical attachment to the armature shaft 84 are movable therewith so that they 115 may be connected with the stationary movement controlling contacts 93 and 94 respectively, as shown, or when the armature has been turned into the opposite position and reverse polar relationship with the field 120 magnet poles, then the contactors 90 and 91 are in connection with the stationary contacts 94 and 95 respectively. It will be noted that the stationary movement controlling contact 95 is free from any connection with the contactors when the armature is in the position shown and that when the armature is in the reverse position, then while the contactors 90 and 91 will be in contact with the stationary contacts 94 and 95 respectively the station- 125 130

ary contact 93 will be free from any contact or connection with the contactors.

As shown the main switch bar or arm 85 is on one end of the armature shaft while the contactors 90 and 91 are shown as being mounted on the other end of the armature shaft. But, it will be understood that this relative dispositoin is not essential and the parts referred to may be mounted in any other position on the armature shaft, or, for that matter, they may be mounted on another shaft and be connected mechanically by a link, lever or otherwise with the main armature shaft, so that the motion of the armature is directly imparted to the shaft on which opening and closing devices are mounted. Or again, if desired, the main switch bar 85 may be mounted directly on the main spindle or shaft while the movement controlling contactors may be mounted on a separate but connected shaft.

The circuit make and break device, located at the control point for the purpose of controlling the action and movement of the electromagnetic mechanism of the remote control switch, is, as shown in connection with the devices of Fig. 6, identical with the similar device used for the same purpose in connection with the devices of Fig. 5. To prevent complication of the arrangements shown in the respective figures, this switch controller also shown in connection with Fig. 6 may be again referred to and its parts indicated by separate characters. This controller has a centrally pivoted contacting lever 96, each end of which is provided with an insulating push button. The ends of the lever are adapted to contact with the two stationary contacts 97 and 98, and as shown contacts at one end with contact 97. Connecting the lever to one side of the main circuit, for instance with wire 89, is a suitable wire or conductor. Stationary contact 97 of the controller is connected by suitable wire with the stationary movement controlling contact 95 on the remote control switch, while the controller contact 98 is connected by a suitable conductor with the movement controlling contact 93 on the remote control switch.

The main switch is shown in the off or open circuit position having been moved into this position by the armature of the electromagnetic actuating device, which due to the current passed through its winding in a particular direction, has been caused to move into the position shown, opening the main switch and swinging the contactors, as indicated by the full line arrow, into the position as shown. Now when the armature by having received a current in its windings in a reverse direction, is caused to move and place itself reversely with re-

lation to the stationary field magnet poles, 65 then the main switch bar and the contactors will be swung back in the opposite direction as indicated by the dotted line arrow, and the main switch will again be closed while the relative position of the contactors with 70 the stationary movement controlling contacts will be changed.

Stationary movement controlling contact 94 it will be noted, is connected with one terminal of the stationary field magnet winding, the other terminal of the field magnet winding being connected to the main circuit wire 87 which is of opposite polarity to wire 89. This connection of the field magnet coil between the wire 87 and the contact 80 85 94 remains fixed and the contact 94 may therefore be called the field magnet line contact of the movement controlling contact device. This contact therefore represents one pole or line wire of the main circuit, the other pole or line wire being represented at 95 and associated with the switch controller, through the lever 96. It will be noted that either one or the other of the two movable armature terminal contactors 90 90 or 91 is in connection with the stationary contact 94 in either the on or the off position of these contactors. That is to say when the contactor 90 is in connection with the contact 93 then the contactor 91 is in 95 connection with the contact 94; and when the contactor 91 is in connection with the contact 95 then the contactor 90 is in connection with the contact 94. The contacts 93 and 95 may be called the on and off 100 contacts of the movement controlling contact mechanism. One of the contactors must be in connection with the contact 93 in order that an on or circuit closing movement of the electromagnetic switch actuating device may be brought about by the proper closing of the control circuit through the switch controller; and to produce the reverse, opposite or off movement of the 105 electromagnetic switch actuating mechanism, one of the contactors must be in connection or contact with the contact 95 which may therefore be called the off contact. The wire connecting 95 with 97 may be called the off controller wire, while the wire connecting 93 with 98 may be called the on controller wire. 110 115

Now, as has been stated above, the diagrammatic showing as indicated in Fig. 6 represents the location and relationship of 120 the parts in the off or open circuited position of the main switch. To bring about a closing motion of the switch it will be necessary to close, at the switch controller, the connection between the lever 96 and the stationary on contact 98, thus breaking the connection between the lever 96 and the stationary off contact 97. With the controller 125

so connected, the circuit through the electro-magnetic switch actuating and control circuit is as follows: from one side of the main circuit 89, to the lever 96, controller on contact 98, controller on wire to the on movement controlling contact 93, the contactor 90 through the armature winding to the contactor 91, to the contact 94, field magnet winding, to the other side of the main circuit, the wire 87. This closing of the circuit causes the current to pass through the armature in such a direction that it will be moved, and due to the magnetic interaction of its poles and the field magnet poles the armature will be moved into the reverse or opposite position. That is to say, the pole of the armature which is shown in proximity to the upper pole of the field magnet will, when moved, be oppositely placed, so that this pole of the armature will be in proximity to the lower pole of the field magnet. In other words, the armature will swing or oscillate over a range of about 90 degrees. This motion of the armature carries with it the switch bar or arm 85 closing the main switch and swinging the contactors into their new or off positions so that the contactor 90, breaking connection with the contact 93, is swung into connection with 94, while the contactor 91, breaking connection with 94, is swung into connection with 95. Thus the on control circuit has been automatically broken or opened and the off control wire has been connected with one terminal of the armature. Connection of the armature terminals has now been reversed. The terminal represented by the contactor 90, which formerly received current through the switch controller from the side 89 of the main circuit, is now in this new position, placed in such connection that it must receive current from the opposite side 87 of the main circuit through the field magnet winding.

If now the remote control switch is to be actuated so as to open the main switch, then, it being assumed that the contactors are in the position as last described and that the main switch is closed, the connection of the arm 96 of the controller with the off contact 97 brings about a current relationship in the control circuit as follows: from one side of the main circuit 89 to the controller bar 86, off contact 97, to the off movement controlling contact 95, contactor 91, armature winding to the contactor 90, the stationary contact 94 through the field magnet winding, and to the other side 87 of the main circuit. This passes the current through the armature windings in the opposite direction and producing such an inter-relationship and inter-action between its poles and the poles of the field magnet as to cause it to be swung back into the open or

off position as shown and bringing its poles 65 into reverse relationship with the poles of the stationary field magnet.

As in the case of the device and arrangements in Figs. 1 to 5 inclusive, the on or the off side of the control circuit is automatically 70 broken or opened at the movement controlling contact devices of the main switch when the switch is actuated in either direction. It is, therefore, unnecessary that the contact also be broken at the switch controller. In 75 fact, it is desirable with this general scheme and arrangement that the controller be of such construction that after the contact has once been established with either the on or the off side it should remain so and not be 80 broken at the controller, this opening or break of the control circuit being provided for as above described. Consequently it is desirable that the make and break device, acting as a controller in conjunction with 85 this type or style of the embodiment of my invention, should be arranged so that the pushing in of the lever 96, or equivalent part, into on or off connection, permits the lever to remain in such connection until it 90 is desired to push it in the opposite position. Such an arrangement and construction is easily provided for in a simple make and break device as indicated, which may be actuated directly or spring actuated as desired, although it is unnecessary to provide a spring snap quick break movement because there is no current to be broken at the controller.

The remote control switch embodying my 100 invention, diagrammatically illustrated in Fig. 7 involves the use of a main switch circuit opening and closing mechanism of somewhat the same order as that used in connection with the arrangement shown in 105 Fig. 5, but, instead of imparting the up and down rectilinear, or reciprocating movement to the switch bars or arms through the medium of a spring snap actuated movement, energy to which is imparted by the rotating 110 motor armature, the movement of the switch bars in Fig. 7 is directly produced by their direct connection and associating with one of the members of the two electromagnetic elements which combine to make the coacting 115 electromagnetic switch actuating device.

The electromagnetic actuating mechanism includes a stationary electro-magnetic element, a polar part of which is indicated by 96. 97 is a movable core of magnetic material having a pole in polar coacting relation to the pole indicated by 96. The stationary magnetic core with which the pole 96 is associated has the winding or coil 98 and the movable core with which the pole 97 is associated has the winding or coil 99. The movable core is extended or mechanically 120 associated so that the switch bars or arms 125

100 are directly mechanically associated or fixed thereto, although insulated therefrom. The contactors 101 and 102 each respectively connect to one terminal of the coil 99 on the 5 movable core which is magnetically associated with coil and may be mechanically connected or fixed thereto. The contactors 101 and 102 are however, insulated from the core and from each other. The coil 98 with its 10 associated stationary core and electromagnetic parts having the pole 96 may be compared with the field magnet and its winding in Figs. 5 or 6, while the coil 99 with its associated movable core having the pole 97, 15 may compare with the moving armature with its winding in Figs. 5 and 6. Consequently, as before, the contactors 101 and 102 are the moving terminals of the armature winding, as it may be called for convenience. 20

Movement controlling stationary contacts, disposed and arranged somewhat similarly to the movement controlling stationary contacts of Fig. 5, are used in coacting association with the contactors 101 and 102. The contact 103 is an on movement controlling contact and is connected by an on wire to the controller contact 107. 106 is an off movement controlling contact and is connected by an off controller wire to the controller off contact 108. The movement controlling contacts 104 and 105 are both connected together and to one terminal of the winding 98, the other terminal of which 35 winding is connected to one side of the main circuit. The movement controlling contacts of the arrangements of Fig. 7 may be compared to the movement controlling contacts of Fig. 5 as follows; contacts 103 and 105 40 are positioned, operate and function in relation to the contactors, substantially as the contacts 20 and 22. Contacts 104 and 106 are located, operate and function in conjunction with the contactors substantially as 45 do the contacts 21 and 23. This being understood, it will be unnecessary to go into any further detailed description of the operation and functioning of these movement controlling devices shown in association with electromagnetic mechanism of Fig. 7, any more 50 than to say that in one position the movable core is attracted to and in the other it is repelled from the stationary core or pole.

The switch controller make and break device shown in conjunction with the scheme and arrangement of this figure is arranged 55 so that connection may be made with either the on or off contact 107 or 108 respectively by means of a connecting arm or bar connected in turn with one wire of the main circuit opposite to the side or wire to which the terminal from the coil 98 is connected. Instead of using however, the centrally pivoted lever contacting at each end, a lever 60 65 tact bar like 109, pivoted at one end and pro-

vided with an insulated handle while the other end is adapted to make contact with either 107 or 108 when moved in the proper position, but ordinarily, in the inoperative, open, or non-switch controlling position the 70 lever is free from connection with either of the contacts 107 or 108. Consequently in manipulating this form of switch controller make and break device, it is necessary to hold the connection, by keeping the lever or 75 arm of the controller in contact with one or the other of the contacts 107 and 108, but this interval is of but short duration inasmuch as the switch actuating mechanism acts directly upon the switch arms or bars 80 instead of through the medium of a spring action which must first be energized by the electromagnetic mechanism before the switch bars or arms are set into movement.

The main switch of the remote control 85 switch represented in Fig. 7 is shown closed across the contacts with which the feed or supply side and the translating side of the main circuit are connected and the movement controlling contacting devices are 90 shown with the contactors acting as the terminals of the armature coil in connection and contact association with the off stationary contacts. In view of the similarity in the relationship and functioning of the 95 parts already described and compared it would be unnecessary in connection with this figure to discuss the current flow through the control circuit when the controller is set to on or off or the manner in which the 100 parts inter-act and co-act, as this will all be well understood from the previous descriptions particularly in connection with the devices of Fig. 5 and is clearly indicated by the diagrammatic circuit representations of 105 Fig. 7.

In order to illustrate the adaptability of the oscillatory or swinging movement electromagnetic switch actuating mechanism to the operation of a rotary or oscillating spring 110 actuated snap switch mechanism, the perspective diagrammatic arrangement of parts, elements, and devices of Fig. 8 has been shown. In this arrangement the electromagnetic actuating mechanism includes a 115 bi-polar field magnet frame 110 and the bi-polar pivoted swinging armature 111. The stationary field magnet frame has the single coil winding 112 while the armature has the winding 113, these windings being arranged 120 on the two members so as to be in concentric mechanical relationship but so disposed through the disposition of the iron parts of each elements, that the polar parts of each are brought into proper magnetic relation 125 one to the other, as indicated in the drawing. The polar relationship and coaction between the armature poles and the field magnet poles in the electromagnetic mechanism of Fig. 8 is substantially the same as that ex- 130

isting in the electromagnetic mechanism of Fig. 6. That is to say the two armature poles, when the current passes through the armature winding in one direction, swing in the direction of the full line arrow, while when the current is passed in the other direction, they swing in the direction of the dotted line arrow placing themselves in relation to the field magnet poles as indicated in the figure which shows the armature position after an on movement, it being understood that when the armature swings back or moves to open or off position, then the polar relationship between the armature and field magnet poles will be reversed, that is to say the armature pole which is now in a close proximity with one of the field magnet poles will then move so as to bring itself into a similar position with the opposite field magnet pole.

The main switch of the arrangement of Fig. 8 consists of insulating base 114 on which are mounted the main circuit contacts 115 these being suitably connected to the current feeding or supply wires and the wires to the translating devices. The movable contact bars or arms 116 are each arranged to contact with a pair of clip contacts 115, so as to make and break connection between each contact pair of contacts dependent upon the position of the coöperating switch bar or arm. These switch bars or arms are mounted on an insulating disk or support 117 and this support, in turn, is mechanically fixed to a sleeve or hollow shaft 118. The switch bars or arms 116 and their connected parts are actuated through the medium of a snap spring movement by the actuating shaft 119 which is so associated with the sleeve 118 through the medium of the spring snap movement, that when turned in either direction, a quick snap spring actuated motion is imparted to the support 117 and the attached switch arms 116, so that these are quickly moved into or out of connection with each of their respective pair of contacts 115. Such snap spring actuated switches are well known in the market and operate so that the manipulation of an actuating member in either direction snaps the movable parts of the contact mechanism, into or out of connection with the stationary contacts of the base.

The switch movement controlling contacting device is shown as being mounted on an insulating base 120. Secured to this base are the stationary contacts 121, 122 and 123. Contact 121 is connected by a suitable wire with one of the contacts 124 of the switch controller, while the other contact 125 of the switch controller is connected by a suitable wire with the contact 122. Contact 123 is connected with one terminal of the field magnet winding 112, while the other terminal of this winding is connected to one side of the main circuit. 126 and 127 are mov-

able contactors serving as terminals of the armature winding 113. The contactors are connected to the ends of the armature winding by means of suitable wires extending through the armature shaft and having a loose and flexible portion extending from the shaft to the insulating support 128 to which the contactors 126 and 127 are fixed in the relative position shown. The insulating support 128 is like the disk or support 117, also secured or fixed to the sleeve or hollow spindle 118, so that when the main switch arms are snapped into or out of connection, the contactors 126 and 127 are also snapped from one movement controlling position to the other.

It will be understood certainly from the showing in the figure that the armature of the electromagnetic mechanism is fixed and secured to the actuating shaft or spindle 119 and that movement of the armature in either direction moves the spindle and causes a corresponding quick snap movement of the main switch and movement controlling contact devices coöperatively associated therewith.

The switch movement controlling contact devices of Fig. 8 are generally similar both in arrangement and functioning to the switch movement contacting devices of Fig. 6. Contact 121 is comparable to contact 95 of Fig. 6 and is an off movement controlling contact, while the contact 122 is comparable to the contact 93 of Fig. 6 and is an on movement controlling contact. Contact 123 is connected, like and serves the same function as contact 94. Similarly the contacts 124 and 125 of the switch controller are off and on controller contacts respectively.

The controller also has the centrally pivoted contacting lever or bar 129, one end of which is adapted to make contact with 124 and the other with 125, and the two ends are provided with insulating push buttons so that the lever may be brought down at either end into connection with one or the other of the two stationary contacts 124 and 125. The lever 129 of this controller, however, instead of being adapted to be pushed and stay down into connection with either the contact 124 or 125, is arranged so that it must be held down into connection for such an interval as may be desired, so that in its normal position the lever 129 is free from connection with either of the stationary contacts. Connection with the lever is made by suitable wire to one side of the main circuit, this connection being opposite to that made by one terminal of the field magnet winding of the actuating mechanism.

The main switch opening and closing mechanism is shown in the closed or on position and the switch movement controlling contacting devices are shown in such association that the proper closing of the con-

troller circuit through the controller on the off side will bring about a current flow in the electromagnetic actuating device to produce the off movement therein. In view of 5 the fact of the similarity between the arrangement, operation and functioning of the switch movement contacting devices and the similar operation and functioning of the two elements of the electromagnetic actuating mechanism of Fig. 8, it will be unnecessary to go into a lengthy description as has been done heretofore and follow out the current paths upon the on or the off operation of the devices shown. This will be 10 clearly indicated from the diagrams and from the description already given, particularly in connection with Fig. 6. It may, however, be stated that whereas in the general scheme and arrangement of the parts 15 of Fig. 6 the main switch mechanism and the switch movement controlling contacting devices move coincidentally with the movement of the movable member of the electromagnetic actuating mechanism, these same 20 devices in the arrangement and scheme of parts of Fig. 8 do not act coincidentally, but while the main switch and the movement controlling contact devices act and move together, the movement of these parts 25 does not occur until after the initial movement of the movable member of the electromagnetic actuating mechanism. In other words, the movement and energy of the electromagnetic actuating mechanism is first 30 imparted to energize the spring of the switch actuating movement, which when released, results in the quick snap action of the contact making and breaking parts and in this 35 feature the arrangement of Fig. 8 is similar to that of Fig. 5 and the structure shown in Figs. 1, 2 and 3.

While I have, for convenience, termed my invention a remote control switch, the term "switch" must be accepted in the broadest 45 sense because, as will be appreciated, my invention is not in any way limited in its adaptability as a mere switch operating appliance in the sense that a switch may be a circuit opening and closing device. The electrical contacting devices actuated by the 50 electromagnetic mechanism, instead of being mere circuit making and breaking devices may serve to alter or change the connection, so that when the actuating mechanism moves 55 into one position these parts are associated together in a certain electrical connection arrangement, while in the other position, they are associated together in another electrical connection arrangement. And, it will 60 also be understood that I may cause to be operated, in conjunction with the contact parts, members or elements, other devices. From the showing above referred to and in the drawings, it will also be understood that 65 embodiments of my invention are not lim-

ited to the utilization of either electromagnetic attraction or repulsion or the combined action of electromagnetic attraction or repulsion, but my invention contemplates in a single electromagnetic actuating device 70 coactingly related electric elements or members which by their combined interaction and coöperation and electromagnetic effect one upon the other, produce movement or motion for the actuation of circuit controlling devices; and furthermore involves the automatic movement control means associated with the electromagnetic mechanism, whereby the elements of the complete electromagnetic actuating mechanism are caused 75 to be so electrically connected, relatively one to the other, that a reverse movement or motion is produced after the actuating device has been caused to function in either direction of its movement. One of the features of my invention involves the actuation of the switching member and movement controlling contact devices, by the electromagnetic actuating device with its two electromagnetically coacting elements, preferably 80 through the medium of a quick acting, snap or spring movement so that the electromagnetic actuating device moves or operates initially to impart its energy to the snap or quick acting movement, the energy 85 of which when released being imparted to the movable switching element and contact devices. The novel construction and arrangement of the particular form of quick acting movements in association with the 90 actuating device and switching and movement controlling contacts also involves structural features of importance.

From the showing of various forms in which my invention may be embodied, it 95 will be understood that I in no way limit myself to the particular form, shape or design of the electromagnetic actuating mechanism or its coacting elements or to the manner in which these are arranged, disposed 100 or placed in magnetically coacting relationship to produce in the one electromagnetic actuating device reverse or opposite movement, motion, actuation or functioning. Nor do I limit myself to any particular 110 form, shape, arrangement, design or disposition of the movement controlling contacts, connections or devices through the automatic actuation of which the electromagnetic actuating device is controlled in any 115 direction of its movement and conditioned in conjunction with the control circuit and controller to act or function differently, oppositely or reversely when again energized. Also while I have shown the electromagnetic 120 actuating device as being both directly and indirectly (through a snapping movement) associated with the switching element and the movable movement controlling parts, it 125 will be understood that I may combine these 130

methods of actuation. Furthermore it is also to be understood that while I have shown the electrical connection reversal of the winding associated with the movable member or element of the electromagnetic actuating device, that exactly similar results are obtained by reversing the electrical connection of the winding associated with the stationary element or member, the other remaining fixed. Or if desired I may provide an electromagnetic actuating device only one member of which has a winding, the other being otherwise provided with proper polar parts (as for instance a permanent magnet).

15. What I claim is:

1. A switch comprising a threaded shaft, means for actuating said shaft in opposite directions, a nut to engage the threads of said threaded shaft, a switching member 20 having an actuating connection with said nut and movable back and forth upon corresponding movements of said nut by said shaft, means between said nut and switching member for accelerating said movement, and means coöperative with said nut to automatically stop its movement on the continued movement of the shaft in either direction.

2. In a switch, a shaft having a threaded portion and an unthreaded portion at each end of the threaded portion, means for moving said shaft in opposite directions, a nut movable back and forth by the threaded portion of the shaft upon opposite movements thereof, a switching member, means connecting the switching member and nut whereby upon opposite movements of the nut the switching member is correspondingly actuated, said nut being adapted at the 40 end of its movement in either direction to travel free of the thread on the shaft, and means for maintaining the nut in position to engage the threaded portion of the shaft at the conclusion of the respective movements of said nut.

3. In an electric switch, a part movable in opposite directions, electrical means for alternately moving said part in said opposite directions, switching means operatively connected with said oppositely movable part, means for alternately effecting operative disconnection of said switching means with said oppositely movable part while at the same time maintaining said switching means in position, relatively to said oppositely movable part, to be operatively reengaged upon the opposite movement of said part, and means automatically operative at or near the conclusion of the movement of the 60 switching means in either direction to stop further movement of the electrical means in the direction producing said movement of the switching means and to change the electrical arrangement of the electrical movement producing means so that when again

energized its movement and the consequent movement of said oppositely movable part will be in the direction opposite to that producing the last prior movement of the switching member.

70

4. In an electric switch, electrical means for producing successive movements, electric circuit controlling means electrically connected with said electrical movement producing means for controlling said movements, a part movable successively by said electrical movement producing means on successive actions thereof, switching means operatively connected with said successively movable part, means for effecting operative disconnection of said switching means with said successively movable part at or near the conclusion of each movement thereof, while at the same time maintaining said switching means in position relatively to said successively movable part to be operatively reengaged upon the next successive movement of said part, and means automatically operative at or near the conclusion of each movement of the switching means to stop further movement of the electrical means producing said movement of the switching means and to electrically arrange it so that when again energized its movement and the consequent movement of said oppositely movable part will produce the next successive movement of the switching member.

85

5. An electromagnetically actuated shaft adapted to be rotatively moved in either direction, a switching element, means in coöperative relation with said shaft whereby said switching element is moved in opposite directions, means associated with the aforesaid means for automatically freeing the coöperative engagement between the shaft and the switch member actuating means at the end of movement in either direction and at the same time retaining said parts in such relationship to permit of their reengagement upon the opposite movement of the shaft and means automatically operative, at or near the conclusion of the movement of the switching element in either direction to stop further movement of the electrical means in the same direction and to change the electrical arrangement so that when again energized, its movement and the consequent movement of said switching element will be in the direction opposite to that producing the last prior movement of the 115 switching element.

100

6. In an electric switch, a part movable in opposite directions, electrical means for alternately moving said part in said opposite directions, a member in coöperative relation with said part and adapted to be moved alternately back and forth thereby on corresponding opposite movement of the part, switching means operatively connected with said oppositely movable member, means for 125

130

alternately effecting operative disconnection of said member with said part, while at the same time maintaining said part and said member in position to be operatively engaged upon the opposite movement of said part, and means automatically operative, at or near the conclusion of the movement of the switching member in either direction, to stop further movement of the 5 electrical means in the same direction and to change its electrical arrangement so that when again energized its movement and the consequent movement of said part will be in the direction opposite to that producing 10 the last prior movement of the switching member.

7. A remote control switch comprising an electric motor, the armature shaft of which is oppositely movable, a member oppositely 20 movable by said shaft and successively on each movement being disengaged therefrom, means for holding the member in position to be operatively engaged by the shaft after it has passed out of engagement therewith, 25 a switching member movable to on and off positions by said member, and means operative with said switching member for controlling the extent of each movement of the motor when the latter is energized and at 30 the same time conditioning said motor to reverse its movement when again energized, and a controller having separate circuit closing positions to effect successive energizations of said motor.

35 8. A threaded shaft, a nut moved by said shaft in opposite directions upon corresponding opposite rotating movement of the shaft, a switch element operatively connected with said nut, and means active at 40 predetermined points in the movement of said nut on said shaft, for automatically disengaging the nut and shaft so far as its further movement in the same direction is concerned, and for permitting the reengagement 45 of the nut with said shaft upon the opposite movement thereof.

9. A switch comprising a threaded shaft, means for turning said shaft in opposite directions, a nut to engage the threads of said 50 shaft, a switching member having an actuating connection with said nut and movable back and forth on corresponding movements of said nut by said shaft, means between said nut and switching member for accelerating said movement, and means for positioning said nut to be engaged by said threaded portion after the nut has completed its opposite movements.

10. In a switch, a switching member, 60 power operable means, means actuated by the power operable means for effecting opposite movements of the switching member and automatically movable out of working relation with said power operable means at 65 predetermined points at opposite movements

of the switching member and means to automatically stop further movement of the power operable means at or near the conclusion of each movement of the switching member and to condition the power operable 70 means to positively prevent repetition of the prior operation and to produce the next successive prior movement of the switching member when the power operable means is again energized. 75

11. The combination of a switching member, power operable means, means actuated by said power operable means for moving the switching member and automatically disengageable therefrom when the switching member has completed a predetermined movement and means to automatically stop further movement of the power operable means at or near the conclusion of each 80 movement of the switching member and to condition the power operable means to positively prevent repetition of the prior operation and to produce the next successive prior movement of the switching member when the power operable means is again energized. 85

12. The combination of a switching member, power operable means, means actuated by said power operable means for moving the switching member and automatically 90 movable out of operating relation with said power operable means when the switching member has completed a predetermined movement, means acting against said means to condition it for operative relation by said 100 power operable means after it is out of said operative relation and means to automatically stop further movement of the power operable means at or near the conclusion of each movement of the switching member and to condition the power operable means to 105 positively prevent repetition of the prior operation and to produce the next successive prior movement of the switching member when the power operable means is again energized. 110

13. The combination of a switching member, power operable means, means actuated by said power operable means for moving the switching member in opposite directions, 115 said means being movable out of working relation with said power operable means when the switching member has reached predetermined points in its opposite movements and means to automatically stop further 120 movement of the power operable means at or near the conclusion of each movement of the switching member and to condition the power operable means to positively prevent repetition of the prior operation and to produce the next successive prior movement of the switching member when the power operable means is again energized. 125

14. A remote control switch comprising an electric motor, the armature shaft of 130

- which is threaded, a nut in engagement with the threaded portion of said armature shaft and movable by said shaft in opposite directions on opposite rotations of said shaft, a
5 switch member movable to on and off positions by said nut, means coöperative with said switching member for governing the extent of each movement of the motor when the latter is energized and at the same time
10 for conditioning said motor to reverse its movement when again energized, and a controller having separate circuit closing positions to effect successive energizations of said motor.
15 15. A remote control switch comprising an electric motor, the armature shaft of which is threaded and is plain at opposite ends of said threaded portion, a nut oppositely movable by the threaded portion of
20 said shaft onto the plain portions thereof,
- means for holding the nut in relation to engage said threaded portion, after it has passed free thereof on opposite rotations of said shaft, a switching member movable to on and off positions by said nut, means operative with said switching member for controlling the extent of each movement of the motor when the latter is energized and at the same time for conditioning said motor to reverse its movement when again energized, 30 and a controller having separate circuit closing positions to effect successive energizations of said motor.

In testimony whereof I affix my signature in presence of two witnesses.

JOSEPH SACHS.
